MACHINE FOR SUCCESSIVELY CONVOLUTING TUBING

Ceril H. Alltop and Garold K. Logsdon, Elgin, Ill., assignors, by mesne assignments, to Dunbar Kapple, Inc., Geneva, Ill., a corporation of Illinois

Application January 19, 1954, Serial No. 405,061

5 Claims. (Cl. 153—73)

This invention relates to a new and improved machine for forming annular convolutions in metal tubing. Tubing thus convoluted is useful in making up flexible metal conduits or hoses, for example.

One object of the present invention is to provide a machine adapted to form an annular convolution in a length of tubing and then to advance the tubing in an improved manner so that succeeding adjacent convolutions may be formed.

Another object of the invention is to provide a machine of the foregoing character having improved means for positively and accurately advancing the tubing so that the successively formed convolutions will be regularly spaced along the tubing.

It is a further object to provide a convoluting machine having improved means for engaging each newly formed convolution and advancing the tubing into position for the formation of an adjacent convolution.

Another object is to provide a convoluting machine in which the advancing of the tubing is accomplished in a minimum of time.

A further object of the invention is to provide a convoluting machine having an improved control system for coordinating the operations of the machine.

It is another object to provide an improved convoluting machine achieving a high rate of production while obviating any possibility of damage to the machine due to improper adjustment or operation.

Further objects and advantages of the invention will appear from the following description of an illustrative embodiment of the invention, as shown in the accompanying drawings, in which:

Figure 1 is a general side elevational view of a convoluting machine constructed in accordance with the invention, certain parts being shown in section and others being removed for clarity of illustration.

Fig. 2 is a fragmentary enlarged transverse elevational sectional view taken generally along a line 2—2 in Fig. 1.

Fig. 3 is a view similar to Fig. 2 but with certain parts of the machine in changed positions.

Fig. 4 is a fragmentary horizontal sectional view taken generally along a line 4—4 in Fig. 2.

Fig. 5 is a view similar to Fig. 4 but with certain parts of the machine in changed positions.

Figs. 6—10 are sectional views illustrating successive stages in the convoluting of tubing. Fig. 6 shows the tubing before being convoluted. Fig. 7 illustrates the tubing in place on the machine. Fig. 8 shows an initial step in the formation of a convolution by means of certain die parts on the machine. Fig. 9 illustrates the final stage in the formation of a convolution. Fig. 10 shows the tubing formed into a flexible metal hose having several convolutions.

Fig. 11 is a wiring diagram illustrating the electrical control arrangement for the machine.

Considered in greater detail, the drawings illustrate a convoluting machine 10 capable of forming narrow

annular convolutions or loops 12 in ordinary cylindrical sheet metal tubing 14 so as to convert the tubing into flexible metal conduit or hose 16 of the type shown by way of example in Figure 10. In the present case, the machine 10 is constructed with a supporting frame 18 comprising a pair of adjacent horizontal beams or main members 20.

To receive and support the cylindrical tubing 14 while it is being convoluted, the machine is provided with an elongated, tubular, horizontal arbor 22 supported solely at its rear end in a heavy block 24 mounted on the rear ends of the main beams 20. In this way, the front end of the arbor 22 is left free so that the tubing 14 may be slipped over the arbor.

15 The individual convolutions are formed in the tubing 14 by means including a hollow female die 26 of annular configuration disposed around one end of the arbor 22. An annular inwardly opening die cavity 28, formed in the interior of the die 26, determines the shape of the convolutions. To provide for radial and axial opening of the die 26, it is formed with four parts 30, 31, 32 and 33. In order that the die 26 may be opened radially, the left hand parts 30 and 32 are mounted on a slide 36 while the right hand parts 31 and 33 are mounted 20 on a slide 37. Both slides are movable laterally relative to the arbor 22 along stationary undercut ways 38 formed on a supporting bed 40. It will be seen that the bed 40 is mounted on the front ends of the beams 20. To provide for axial opening of the die 26, the front parts 30 and 31 are mounted on longitudinally movable slides 42 and 43, while the rear die parts 32 and 33 are mounted directly on the laterally movable slides 36 and 37. In this case, the slides 42 and 43 are movable along undercut ways 44 and 45 formed on the slides 36 and 37. 25 Upright die holders 46, 47, 48 and 49 are mounted on the slides 42, 43, 36 and 37 to support the die parts 30—33.

For the purpose of effecting radial opening and closing of the die 26, the convoluting machine 10 is equipped 30 with suitable power actuating means, such as the illustrated double-acting fluid cylinders 52 and 53, connected to the die holders 46 and 47 on the laterally movable slides 36 and 37, the cylinder being operated by air in this instance, although hydraulic actuation would also be suitable for these cylinders and the others to be described shortly. Axial opening and closing of the die 26 is effected by means of a similar double-acting air cylinder 54 mounted underneath the beams 20. To connect the air cylinder 54 to the axially movable slides 42 and 43, a generally vertical lever 55 is pivotally mounted on the beams 20 and is pivotally connected at its lower end to the air cylinder. A link 56 is connected between the upper end of the lever 55 and the slides 42 and 43, the connection being such as to permit the lateral movement of the slides. In this case, the rear end of the link 56 may be connected to a cross bar 57 slidably received in a pair of slots 58 formed in the front ends of the slides 42 and 43.

60 To expand the cylindrical wall of the tubing 14 into the cavity 28 in the annular die 26, the outer end of the arbor 22 is fitted with an expandable die 60, in the form of a compressible rubber disk disposed between a pair of collars 61 and 62. The rear collar 61 may have a 65 reduced portion 63 fitted within the outer end of the hollow arbor 22. In order that the tubing 14 may be slipped easily over the arbor 22, the front collar 62 may be tapered forwardly.

To compress the rubber die 60 and thereby expand it 70 outwardly into the die cavity 28, a rod 66 is arranged to extend through the arbor 22, the die 60 and the collars 61 and 62. The outer end of the rod 66 is fitted with a

pair of nuts 67 to provide an abutment engageable with the outer collar 62.

The rod 66 is actuated in this instance by means of a double acting air cylinder 70 mounted under the beams 20 at the rear end of the arbor 22. A lever 71, pivotally mounted on the block 24, is pivotally connected adjacent its opposite ends to the rod 66 and the air cylinder 70, the arrangement of the lever arms being such as to provide a considerable mechanical advantage for compressing the rubber die 60.

After the dies 26 and 60 have formed an annular convolution, the tubing 14 is indexed along the arbor 22 by an indexing mechanism 74 comprising a sleeve 75 disposed around the arbor 22 immediately to the rear of the annular die 26. The size of the sleeve 75 is such that it will receive the tubing 14 with a sliding fit. Reciprocation of the sleeve 75 may be effected by means of a double acting air cylinder 76 connected to the lower end of a lever 77 by means of a link 78. Two links 79 are employed to connect the bifurcated upper end of the lever 77 to the sleeve 75. After the dies 26 and 60 have formed a convolution, the sleeve 75 is advanced so as to engage the convolution and move the tubing 14 into position for the formation of another adjacent convolution.

Compressed air to operate the machine 10 is obtained from an air line 81. The operation of the machine is controlled by means of electrically operable solenoid reversing valves 82, 83, 84, 85 and 86 connected between the air line 81 and the respective air cylinders 52, 53, 54, 70 and 76. The valves 82-86, which may be of well known construction, are adapted to supply compressed air to the opposite ends of the air cylinders. Each of the valves 82-86 may be provided with a pair of solenoids 87 and 88. Momentary energization of the solenoid 87 will shift the valve into one position and thus supply air to one end of the particular cylinder. Likewise, momentary energization of the other solenoid 88 will reverse the setting of the valve so as to supply air to the opposite end of the cylinder. In each case, the end of the cylinder not supplied with air is vented through the valve to the atmosphere. One end of the solenoid 87 is connected to a terminal 89 while the other end is connected to a grounded terminal 90. The solenoid 88 is connected between the grounded terminal 90 and a terminal 91.

To operate the air cylinders 52, 53, 54, 70 and 76 in the proper sequence, the machine 10 is provided with a timing device 100 which, in this instance, comprises seven cams, 101, 102, 103, 104, 105, 106, and 107, driven by an electrical motor 108. As indicated diagrammatically in Figure 11, all of the cams may be mounted on a single shaft 109. During the greater part of the cycle of operations, the motor 108 is energized from alternating current power line wires 109 and 110. A master switch 111 may be connected in series with the line 110 to control the energization of the motor 108 and the other elements of the control system.

To supply power for operating the electrical valves 82-86, the illustrated control system is equipped with three step down transformers 114, 115 and 116 having the ends of their primary windings connected to the line wires 109 and 110. Each of the transformers 114-116 has its secondary winding arranged with one end grounded. The other ends of the windings are brought out to ungrounded terminals 117, 118 and 119.

To control the energization of the electrical valves 82-86, the cams 101-107 are arranged to operate respective normally open switches 121, 122, 123, 124, 125, 126 and 127. Each of the cams 101-107 is provided with a projecting cam lobe 128 adapted to effect momentary closure of the corresponding switch.

In this instance, the first cam 101 is employed to initiate the cycle of operations by closing the die 26 radially. To this end, the switch 121 associated with this cam 101 is connected in series with a lead 131 extending between

the ungrounded transformer secondary terminal 117 and one ungrounded terminal of each of the valves 82 and 83 mounted on the air cylinders 52 and 53. Closure of the switch 121 at the beginning of the cycle of operations will operate the valves 82 and 83 in such a direction that the cylinders 52 and 53 will move the slides 36 and 37 toward each other and thus will close the die 26 radially.

In order to expand the rubber die 60 simultaneously with the closure of the annular die 26, the first and second cams 101 and 102 are arranged with their projecting lobes 128 substantially aligned so that the switches 121 and 122 will be closed at the same time. The switch 122 is connected in series with a lead 132 extending between the ungrounded transformer terminal 118 and the ungrounded terminal 91 of the solenoid valve 85. When the cam 102 closes the switch 122, the valve 85 will supply air to the rear end of the air cylinder 70 and the cylinder will thus cause the lever 70 to exert a pull on the rod 66 so as to compress the rubber die 60. As a result, the die 60 will expand the cylindrical wall of the tubing 14 into the die cavity 28.

For the purpose of contracting the rubber die 60, the switch 123 associated with the third cam 103 is connected in series with a lead 133 extending between the ungrounded transformer terminal 118 and the ungrounded terminal 89 of the solenoid valves 85. The cam 103 is oriented so that its protruding lobe 128 will close the switch 123 after the switches 121 and 122 have been opened. As a result, the setting of the solenoid valve 85 will be reversed and air will be supplied to the front end of the cylinder 70 so as to push the rod 66 back into its initial position and permit contraction of the die 60.

In order to compress the newly formed convolution axially, so that it will assume its final form, the fourth cam 104 is arranged to close the die 26 axially. To this end, the switch 124 is connected in series with a lead 134 extending between the transformer secondary terminal 119 and one ungrounded terminal of the solenoid valve 84. The cam 104 is arranged to close the switch 124 after the die 60 has been contracted by the operation of the switch 123. The closure of the switch 124 will result in shifting of the valve 84 to such a position that the air cylinder 54 will move the front die parts 30 and 31 toward the rear die parts 32 and 33. The die parts preferably are brought into closely contiguous relation but not into actual engagement in order to avoid an impact between the die parts.

The axial closing of the die 26 completes the formation of the convolution 12 and thus the next step is to open the die 26 so that the tubing 14 may be advanced into position for the formation of another convolution. For this purpose, the fifth and sixth cams 105 and 106 are arranged to open the die 26 axially and radially at the same time. Thus the switch 125 is connected in series with a lead 135 extending between the transformer terminal 117 and one ungrounded terminal of each of the solenoid valves 82 and 83. Closure of this switch will result in radial separation of the die parts 30 and 32 from the parts 31 and 33. The switch 126 is connected in series with a lead 136 extending between the ungrounded transformer terminal 119 and one ungrounded terminal of the reversing valve 84. When the switch 126 is closed, the valve 84 is shifted to a position such that air will be supplied to the front end of the cylinder 54. This will result in movement of the front die parts 30 and 31 away from the rear die parts 32 and 33.

In order to advance the tubing 14 into position for the formation of another convolution the switch 127, associated with the cam 107, is connected in series with a lead 137 extending between the ungrounded transformer terminal 118 and one ungrounded terminal on the solenoid reversing valve 86 mounted on the indexing cylinder 76. The seventh cam 107 is oriented so as to close the switch 127 after the die 26 has been opened

radially and axially by the operation of the cams 105 and 106. When the switch 127 is closed, the cylinder 76 will advance the indexing sleeve 75 into engagement with the newly formed convolution 12. The stroke of the indexing cylinder 75 is such as to advance the tubing 14 into position for the formation of another convolution.

When the sleeve 75 is thus advanced it moves into the annular die 26 and thus is vulnerable to damage in the event that the die should close prematurely. However, in accordance with one aspect of the present invention, the machine is arranged so that closure of the die 26 will be prevented until the indexing sleeve 75 has been fully withdrawn. This is true even though the movement of the sleeve 75 may be retarded due to friction, low air pressure or any other cause. To prevent closure of the die 26, a rear limit switch 140 is arranged to be held closed when the sleeve 75 is in its normal retracted position. As shown, the switch 140 may be operated by the upper end of the lever 77. In this instance, the switch 140 is connected in a series circuit 141 which includes the timing motor 108 and is connected between the power lines 109 and 110. When the cylinder 76 advances the sleeve 75, the switch 140 will open and thus will stop the motor 108. The operation of the motor 108 will not be resumed until the sleeve 75 again returns to its fully retracted position. Only then will the cam 101 be advanced to a position such as to close the switch 121 controlling the closure of the die 26.

It will be understood that the closure of the sleeve advancing switch 127 by the cam 107 is only momentary, such momentary closure being sufficient to shift the valve 86. Even before the motor 108 is stopped by the opening of the rear limit switch 140, the cam 107 is advanced to a point such as to open the switch 127 and thus condition the valve 86 for a subsequent reversal.

In order to provide for retraction of the sleeve 75 even though the timing device 109 has been disabled, a front limit switch 143 is arranged to be closed when the sleeve 75 has been fully advanced. In the illustrated construction, the switch 143 is operated by the upper end of the lever 77. In this instance, the switch 143 is in series with a lead 144 connecting the ungrounded transformer terminal 118 to one ungrounded terminal on the solenoid reversing valve 86. Thus, the closure of the front limit switch 143 will be effective to reverse the valve 86 and thus initiate retraction of the sleeve 75.

With the sleeve 75 retracted, the rear limit switch 140 will again be closed to start the motor 108 and initiate another cycle of operations. The cycle may be repeated indefinitely until the desired number of convolutions 12 has been formed in the tubing.

Although the operation of the machine has already been described and will be clear from the foregoing description, a brief resume may be of some assistance. Initially, a length of the tubing 14 is slipped over the outer end of the arbor 22. Closure of the main switch 111 will then initiate a cycle of operations. The first step in the cycle is to close the die 26 radially and simultaneously expand the rubber die 69. The cams 101 and 102 initiate these operations by closing the switches 121 and 122 to shift the valves 82, 83 and 85 so that the cylinders 52 and 53 will close the die 26 and the cylinder 70 will expand the rubber die 69.

Radial closing of the die 26 and expansion of the rubber die 69 results in the formation of a convolution which is wider and smaller in diameter than the desired final form. In order to compress the convolution axially so that it will become narrower and larger in diameter, the rubber die 69 is first contracted by operation of the cam 103. Then the annular die 26 is closed axially by the action of the cam 104, which closes the switch 124 and thus initiates operation of the air cylinder 54 so as to move the front die parts 30 and 31 into contiguous relation with the rear die parts 32 and 33.

Next in the cycle, the cams 105 and 107 act simultaneously to open the die 26 radially and axially through the medium of the air cylinders 52, 53 and 54. After the die 26 has been opened, the cam 107 closes the switch 127 and thus causes the air cylinder 76 to advance the indexing sleeve 75 so that it will engage the newly formed convolution and move the tubing forwardly on the arbor 22 into position for the formation of another convolution.

Initial forward movement of the indexing sleeve 75 opens the rear limit switch 140 and thereby stops the timing motor 108 so that the advancing movement of the cams 101-107 will be suspended. In this way, premature closing of the die 26 is prevented. However, there is sufficient delay in the operation of the valve 86 and the air cylinder 76 to permit the cam switch 127 to open before the motor 108 stops. Thus when the indexing lever 27 closes the front limit switch 143 at the completion of the indexing movement, the valve 86 will be reversed and the sleeve 75 will be retracted. This will again close the rear limit switch 140 to initiate another cycle of operations.

It will be evident that the arrangement of the limit switches 140 and 143 positively obviates any possibility of damage to the indexing sleeve 75 due to premature closing of the annular die 26. Moreover, the use of the front limit switch 143 to initiate retraction of the sleeve 75 results in the tubing being indexed in the minimum possible time. Because of the safety feature provided by the rear limit switch 140, the cams may be set so that the first switch 121 will be closed immediately after the motor 108 is started. In this way, there will be a minimum of delay in the initiation of each cycle of operations.

While details of the exemplary machine have been described and illustrated it will be understood that there is no intention to limit the invention to such details. Rather the invention is to cover all modified constructions, alternatives and equivalents falling within the spirit and scope of the invention as defined in the following claims:

We claim as our invention:

1. A machine for convoluting tubing comprising an arbor for receiving the tubing, a hollow annular die around one end of said arbor, said annular die having a plurality of parts arranged for radial and axial opening of said die, a plurality of reciprocable fluid motors for opening said die axially and radially, an expandable die at said one end of said arbor in the form of an axially compressible and radially expandable rubber disk for expanding the tubing partway into said annular die and thereby partially forming a convolution, means including a draw rod extending through said disk and said arbor for compressing said disk, a reciprocable fluid motor connected to said draw rod for expanding and contracting said disk, a sleeve disposed around said arbor for receiving the tubing, means including a reciprocable fluid motor for reciprocating said sleeve along the tubing to enter said annular die, engage the newly formed convolution and advance the tubing into position for the formation of an adjacent convolution, control means for controlling said fluid motors and including a plurality of electrically operable control valves therefor, a plurality of timing cams, an electrical motor for driving said cams, a plurality of switches operable by said cams and connected to said valves for sequentially closing said annular die radially, expanding and then contracting said expandable die, closing said annular die axially to complete the convolution, opening said annular die radially and axially and advancing said sleeve, a rear limit switch operable by initial advancing movement of said sleeve for disabling said electrical motor and thereby preventing premature closure of said annular die and a front limit switch operable by complete advancement of said sleeve for retracting said sleeve.
2. A machine for convoluting tubing comprising an arbor for receiving a length of the tubing, a hollow radially and axially openable annular die around one end of said arbor, an expandable die within said annular die and on

said one end of said arbor for expanding the tubing partway into said annular die and thereby partially forming an annular convolution in the tubing, a sleeve on the arbor and reciprocable along the tubing for engaging the newly formed convolution and advancing the tubing into position for formation of an adjacent convolution, control means for successively closing said annular die radially, expanding and then contracting said expansible die, closing said annular die axially, said convolution thereby being completed opening said annular die radially and advancing said sleeve, means operable by initial advancing movement of said sleeve for disabling said control means and thereby preventing closure of said annular die, and means for retracting said sleeve and reinitiating operation of said control means.

3. A machine for convoluting tubing comprising an arbor for receiving the tubing, a hollow annular radially and axially openable die around one end of said arbor, an expansible die within said annular die and on said one end of said arbor for expanding the tubing partway into said annular die and thereby partially forming a convolution in the tubing, a sleeve reciprocable on said arbor and receivable over the tubing for engaging the newly formed convolution and advancing the tubing into position for formation of a succeeding convolution, control means for successively closing said annular die radially, expanding said expansible die, contracting said expansible die closing said annular die axially, said convolution thereby being completed, opening said annular die radially and advancing said sleeve, means operable by initial advancing movement of said sleeve to suspend operation of said control means to prevent closure of said annular die, and means operable at the completion of the advancing movement of said sleeve for retracting said sleeve and thereby reinitiating operation of said control means.

4. A machine for convoluting tubing comprising an arbor for receiving the tubing, a hollow annular die around one end of said arbor, said annular die having a plurality of parts arranged for radial and axial opening of said die, power means for opening said die radially, an expansible die at said one end of said arbor for expanding the tubing partway into said annular die and thereby partially forming a convolution, power means for expanding and contracting said expansible die, a sleeve disposed around said arbor for receiving the tubing, power means for reciprocating said sleeve along the tubing to enter said annular die, engage the newly formed convolution and advance the tubing into position for the

formation of an adjacent convolution, control means in controlling relation to said power means for sequentially closing said annular die radially, expanding and then contracting said expansible die, closing said annular die axially, said convolution thereby being completed, opening said annular die radially and advancing said sleeve, a rear limit control device operable by initial advancing movement of said sleeve for disabling said control means and thereby preventing premature closure of said annular die and a front limit control device operable by complete advancement of said sleeve for effecting retraction of said sleeve and thereby reinitiating operation of said control means.

5. A machine for convoluting tubing comprising an arbor for receiving the tubing, a hollow annular die around one end of said arbor, said annular die having a plurality of parts arranged for radial and axial opening of said die, power means for opening said die axially and radially, an expansible die at said one end of said arbor in the form of an axially compressible and radially expansible rubber disk for expanding the tubing partway into said annular die and thereby partially forming a convolution, means including a draw rod extending through said disk and said arbor for compressing said disk, power means connected to said draw rod for expanding and contracting said disk, a sleeve disposed around said arbor for receiving the tubing, power means for reciprocating said sleeve along the tubing to enter said annular die, engage the newly formed convolution and advance the tubing into position for the formation of an adjacent convolution, timing means in controlling relation to said power means for sequentially closing said annular die radially, expanding and then contracting said expansible die, closing said annular die axially to complete the convolution, opening said annular die radially and axially and advancing said sleeve, a rear limit control device operable by initial advancing movement of said sleeve for disabling said timing means and thereby preventing premature closure of said annular die and a front limit control device operable by complete advancement of said sleeve for retracting said sleeve.
